UNITED STATES PATENT OFFICE.

LARUS FRÜS CARSTENSEN, OF BRIDGEPORT, CONNECTICUT.

BICYCLE.

SPECIFICATION forming part of Letters Patent No. 398,228, dated February 19, 1889.

Application filed November 21, 1888. Serial No. 291,478. (No model.)

To all whom it may concern:

Be it known that I, LARUS FRÜS CARSTENSEN, a citizen of the United States, residing at Bridgeport, in the county of Fairfield and State 5 of Connecticut, have invented certain new and useful Improvements in Bicycles; and I do hereby declare the following to be a full, clear, and exact description of the invention, such as will enable others skilled in the art to which 10 it appertains to make and use the same.

My invention has for its object to simplify and cheapen the construction of this class of machines and to greatly improve their operation in use. With these ends in view I have 15 devised the novel construction of which the following description, in connection with the accompanying drawings, is a specification, numbers being used to denote the several parts.

20 Figure 1 is an end elevation of one of the hubs; Fig. 2, a side elevation thereof; Fig. 3, a longitudinal section on the line $z z$ in Fig. 4, looking toward the left; Fig. 4, a section on the line $x x$ in Fig. 3; Fig. 5, a similar section 25 illustrating certain changes in the details of construction; Fig. 6, a section on the line $y y$ in Fig. 3; and Fig. 7 is an elevation and edge view of a special style of spring used in the form illustrated in Fig. 5.

30 Similar numbers denote the same parts in all the figures.

1 denotes the axle, having a flange, 2, and a threaded portion, 3; 4, the hub, which is threaded to engage the threaded portion of 35 the axle and is turned up tightly against the flange; and 5, the spokes, which are connected in any suitable manner to the hub.

6 denotes the drum; 7, the ball-case; 8, the fork, which is bolted to a lug, 9, on the ball-40 case; 10, the fulcrum, which is forged integral with or rigidly secured to the ball-case; 11, the pedal-lever, the foot-rest and the pivotal point to the fulcrum not being shown; and 12, the chain, one end of which is attached to the 45 pedal-lever and the other to the periphery of the drum, the point of attachment not being shown, as it is not an essential feature of my invention. By making the fulcrum rigid with the ball-case and placing the latter outside 50 the drum I do away with the wobbling motion which exists in many machines of this

class and secure greatly-increased firmness and rigidity. The drum is made in a single piece, its construction being clearly shown in Fig. 3.

Within the hub is an extension, 13, of the drum, having a flange, 14, which forms, with the back of the drum, a circular box, in which the pawls 15 are pivoted, as will presently be more fully explained.

Within the drum is a strong spring, 16, one end of which is attached to the inner periphery of the drum by a hook, 17, formed by bending over the end of the spring itself, which engages any one of a series of lugs, 18, formed 65 upon the drum. (See Fig. 6.) The other end of the spring is connected to an angle-plate, 19, which lies against the hub 20 of the drum, and the outer end of which is recessed into the ball-case, being secured thereto by screws, 70 as shown in Fig. 3, or in any suitable manner. The inner end of the angle-plate is provided with a notch, which is engaged by a hook, 21, at the inner end of the spring, as clearly shown in Fig. 6. The outer end of the drum is closed 75 by a plate, 6^a, secured to the drum by screws, as shown in Fig. 1. Upon the inner periphery of the hub is a ratchet, 22, rigidly secured thereto, preferably by screw-threads formed upon both parts, as shown in the drawings. 80 This ratchet is adapted to be engaged by the pawls 15, as clearly shown in Fig. 4, said pawls being pivoted to the extension in the drum within the hub in any suitable manner, preferably as shown in Fig. 3.

23 denotes a friction device, which bears against the ratchet. This device may be made of metal, wood, vulcanite fiber, or any suitable material. In practice I ordinarily use ebony wood. It is provided with a shank, 90 24, adapted to slide in a holder, 25. A spring, 26, (see dotted lines, Fig. 4,) acts to press the friction device outward against the ratchet. If preferred, the friction device itself may be made of spring metal. The holder is shown 95 as having arms 27, and is connected by links 28 to the pawls. It will of course be apparent that the axle and hub must turn forward together, the direction of movement being indicated by the arrow in Fig. 4. The drum has 100 independent movement on the axle, and the ball-case is of course stationary. The ratchet

is wholly silent in operation. When the pedal-lever is pressed down, the pawls instantly engage the ratchet, so that the entire power is applied to the hub by means of the chain, drum, and pawls, thereby carrying the machine forward. The downward movement of the pedal-lever being against the power of spring 16, it of course follows that the instant the downward pressure upon the pedal-lever is relieved the spring will turn the drum backward, thereby winding the chain thereon. In use the pedal-levers are ordinarily pressed downward alternately, so that the application of power to the wheel is continuous. The instant the power is removed and the spring 16 begins to act to turn the drum and extension 13 backward and to wind the chain the friction device will drag upon the ratchet, the effect of which is to tilt holder 25, and by means of the links to throw the pawls out of engagement with the ratchet. The instant power is applied to the pedal-lever again holder 25 is tilted in the opposite direction, and the pawls are caused to engage the ratchets, as before. It will thus be seen that the pawls never drag upon the ratchet, but are either perfectly engaged therewith or wholly disengaged, the engagement or disengagement taking place the instant the movement of the drum is reversed. In the form illustrated in Fig. 5 the construction is the same, except that the friction device acts against an inner shoulder, 29, upon the hub instead of against the ratchet. The friction device in this form consists of a circular spring, which I have denoted by 23^a, (see Fig. 7,) said spring being provided with a lug, 24^a, for engagement with the holder. (See Fig. 5.) In order to avoid an extra figure in the drawings, I have shown shoulder 29 and friction device 23^a in Fig. 3, it being of course understood that either form of friction device may be used. It will furthermore be apparent that the section-line of Fig. 5 is such that spring 23^a would not show therein. I have, however, indicated its position by dotted lines. The operation is precisely the same as in the other form. The instant power is removed spring 16 acts to reverse the movement of the drum. The friction of spring 23^a upon shoulder 29 will retard the motion of the hub by dragging thereon, which will tilt the holder and disengage the pawls, as before.

It should be noted as an important feature of my invention that the organization is compact, the hub and drum lying close together and the ball-case being placed on the outer side of the drum. This feature of construction is especially valuable, as it enables me to place the bearings at the greatest possible distance apart on the axle, thereby greatly increasing the strength of the machine and the steadiness of its movement. So far as I am aware, in all bicycles of this class heretofore constructed the fulcrum has been attached to the fork, the organization being such that it was impossible to attach it to the ball-case.

In the present instance it will be noticed that the ball-case and fulcrum are made integral. At each end of the axle—one end only being 70 shown in the drawings—are two reversed cones, 30 and 31. The end of the axle is provided with a screw-thread, 32, and the cones are internally screw-threaded to engage therewith, the inner cone, the incline of which 75 is outward, being screwed up tight against a shoulder on the axle, as at 33. On the interior of the ball-case, at the inner end thereof, is an incline, 34. The outer end of the ball-case is provided with an internal screw-thread, 35, which is engaged by a ring, 36, having external screw-threads corresponding with those upon the ball-case, and also having an incline, 37, corresponding with incline 34 upon the ball-case. 80 The opening in ring 36 is closed by the outer cone, 31, which, as already stated, is screw-threaded to engage the thread upon the axle, the incline of the outer cone being inward and corresponding with the outward incline upon the inner cone. The anti-friction device consists of a duplicate series of balls, 38, the opposite balls being connected by a cross-bar, 39. One ball in each pair is therefore in engagement with incline 34 upon the 95 ball-case and the incline upon the inner cone, and the other ball being in engagement with incline 37 upon ring 36 and the incline upon the outer cone. The special advantages of this construction are its great strength, the 100 steadiness with which it causes the machine to run, and the perfection and simplicity of its adjustment. The adjustment is effected by turning in the outer cone as much as may be found necessary, and locking it with a check-nut, 40, and turning in ring 36, and locking it by a key, 41, the perimeter of the outer end of the ring being preferably notched, as shown, and the key provided with teeth to engage the notches. 110

Having thus described my invention, I claim—

1. In a bicycle, the combination, with a hub, a ratchet within the hub, and a spring-controlled drum having an extension within the 115 hub to which the pawls are pivoted, of a ball-case and fulcrum outside of the drum, and a fork attached to the ball-case, so that the bearings are placed at the greatest possible distance apart and the weight is placed directly upon the bearings. 120

2. In a bicycle, a rotating axle, hub, and ratchet, a drum turning on the axle, and a ball-case placed outside of the hub and drum, and having a fulcrum made integral therewith and a fork attached thereto. 125

3. The combination, with the hub and drum, of the ball-case placed outside of both and a fulcrum and fork connected to the ball-case, as and for the purpose set forth. 130

4. A ball-case having incline 34 and ring 36, threaded to engage the interior of the ball-case, and having an incline, 37, in combination with the axle having reversed cones and a

duplicate series of balls connected by cross-bars which engage said cones and inclines.

5. The combination, with the ball-case having incline 34 and ring 36, threaded to engage the ball-case, and having incline 37, of the axle threaded at its outer end and having a shoulder, 33, a cone, 30, resting against said shoulder and having an outward incline, a cone, 31, engaging the screw-thread and 10 having an inward incline, and pairs of balls connected by cross-bars engaging said inclines and cones.

6. The ball-case having incline 34, ring 36, threaded to engage the ball-case, and having 15 incline 37, in combination with the cones having reversed inclines, as shown, balls connected by cross-bars engaging said inclines and cones, and means, as a check-nut, engaging the axle, and a key engaging the ring, 20 whereby the parts are secured in place after adjustment.

7. The axle having a shoulder, 33, and a screw-thread, 32, the ball-case having an incline, 34, and the fork secured to the ball-case, 25 in combination with ring 36, having incline 37, inner and outer cones having reversed inclines, the inner cone engaging shoulder 33, and a duplicate series of balls connected by cross-bars and engaging the inclines and the 30 cones.

8. The ball-case and ring 36, having inclines, as shown, the ring being threaded to engage the ball-case, in combination with the axle having a screw-thread, inner and outer 35 cones engaging the axle, a duplicate series of balls connected by cross-bars which engage the inclines and cones, said ring having notches, as shown, which are engaged by a key, 41, to lock it in position, and a check-nut 40 engaging the outer cone to lock that in position.

9. The axle and the inner and outer cones, the latter being adjustable, the ball-case having an incline, and the adjustable ring engaging 45 the ball-case, and also having an incline, in combination with a duplicate series of balls connected by cross-bars, the bearing being adjusted by turning the outer cone and ring inward, as described.

50 10. In a bicycle, the combination, with a rotating axle and hub, and ratchet and pawls within the hub, of a drum having lugs 18 on its inner periphery, spring 16, engaging either of said lugs, and an angle-plate secured to the ball-case and extending within the drum, to which the inner end of the spring is connected.

55 11. The drum having extension 13 and a spring, 16, within the drum, in combination

with the rotating axle, hub, and ratchet, pawls pivoted to said extension and engaging the 60 ratchet, and a friction device to which the pawls are connected, whereby when the backward movement of the drum commences the pawls are disengaged from the ratchet, as and for the purpose set forth. 65

12. The rotating axle, hub, and ratchet, in combination with the drum, pawls pivoted thereto and engaging the ratchet, and a friction device consisting of a holder, 25, pivoted to the drum, links connecting said holder with 70 the pawls, and a spring-actuated friction-piece which engages the ratchet when the backward movement takes place, whereby the holder is tilted and the pawls disengaged from the ratchet. 75

13. The hub rigidly secured to the rotating axle and the ratchet secured to the hub, in combination with the drum and extension 13, turning on the axle, a spring within the drum, whose outer end is connected thereto, its inner end being connected to a fixed angle-plate, pawls pivoted to the extension and engaging the ratchet, and a friction device within the hub, which disengages the pawls when the reverse movement begins. 80 85

14. The ball-case having angle-plate 19, connected thereto and the fulcrum made integral therewith, in combination with the hub, drum, ratchet, pawls, and friction device acting as described, and a spring within the drum, whose 90 outer end is adjustably connected thereto, its inner end being connected to the angle-plate.

15. The ball-case and fulcrum made integral and the fork connected to the ball-case, in combination with the rotating axle, hub, 95 and ratchet, the drum turning on the axle, the spring within the drum, and the pawls and friction devices, arranged as described, whereby the entire weight is supported by the bearings which are placed at the greatest 100 possible distance apart, as and for the purpose set forth.

16. The drum having extension 13 and flange 14 and the hub and ratchet, in combination with the pawls pivoted between said flange 105 and the drum and a friction device carried by a holder pivoted to the drum, and links connecting said holder with the pawls, as and for the purpose set forth.

In testimony whereof I affix my signature in 110 presence of two witnesses.

LARUS FRÜS CARSTENSEN.
